(57) **CLAIM**

The ornamental design for a modular hanging display, as shown and described.

DESCRIPTION

FIG. 1 is a perspective view of a modular hanging display including two display modules.

FIG. 2 is a front elevation view of the modular hanging display.

FIG. 3 is a right side elevation view of the modular hanging display.

FIG. 4 is a rear elevation view of the modular hanging display.

FIG. 5 is a left side elevation view of the modular hanging display.

FIG. 6 is a top view of the modular hanging display.

FIG. 7 is a bottom view of the modular hanging display.

FIG. 8 is an enlarged fragmentary view of a connecting part, provided for clarity, taken from the circled area 8—8 in FIG. 1.

FIG. 9 is a perspective view of a second embodiment of the modular hanging display of FIGS. 1-8, the only difference being that the display module panels are light-transmissive, it being understood that all other surfaces are the same as those of the first embodiment; and,

FIG. 10 is a perspective view of the modular hanging display of FIG. 9, showing one display module removed from the display for clarity of disclosure, it being understood that all other surfaces are the same as those of the second embodiment.

The broken lines are directed to the environmental structure and form no part of the claimed design.
